UNITED STATES PATENT OFFICE.

JOHN J. ROTH, OF DAYTON, OHIO.

PHOTOGRAPHIC-PRINTING MACHINE.

1,414,582.

Specification of Letters Patent.

Patented May 2, 1922.

Application filed January 7, 1920. Serial No. 349,969.

To all whom it may concern:

Be it known that I, JOHN J. ROTH, a citizen of the United States, residing at Dayton, in the county of Montgomery and State 5 of Ohio, have invented certain new and useful Improvements in Photographic-Printing Machines, of which the following is a specification.

The principal object of the invention is 10 to provide in a photographic printing machine, simple and efficient means for automatically obtaining contact during the exposure of the printing paper. In machines as at present constructed, it is necessary to 15 hold the contact lid against the printing glass by hand, or through spring catches or other engaging elements. This not only involves unnecessary labor, but inferior contact where the contact lid is not held tightly 20 against the printing glass by the operator. My improved means for insuring contact contemplates the use of a roll-top lid which makes the contact operation automatic without the use of catches, and leaves both hands 25 of the operator free.

Other important and incidental objects will be brought out in the following specification and particularly set forth in the subjoined claims.

30 The preferred form of embodiment of my invention is illustrated in the accompanying drawings, of which Figure 1 is a side elevational view of my improved machine. Figure 2 is a top plan view of the contact lid. Figure 3 is a side elevational view of the contact lid resting over the printing glass. Figure 4 is a front view of the printing machine. Figure 5 is a front view of the carriage, showing the front contact 35 spring secured thereto. And Figure 6 is a front view of the front roller and felt which passes around it.

Throughout the specification and drawings, similar reference characters denote corresponding parts.

Referring to the accompanying drawings, the numeral 1 designates the top of a photographic printing machine, which contains the usual printing opening 2 that is covered 50 by a glass 3 whose top is flush with the top surface of the printing machine top 1.

Permanently secured to the top 1 of the printing machine, immediately behind and at each side of the printing opening 2, is a 55 bracket 4 from the upper middle portion of which there projects inwardly an arm 5.

The inner end of each arm 5 terminates in a core 6 for a ball bearing race 7 containing balls 8 over which an elongated tube 9 is adapted to travel. (See Figures 4 and 5.) 60 The arms 5 in which the ball bearing races 7 are provided, project loosely into the tubes 9 through slots 10 longitudinally formed in the latter, whereby said tubes may have a free movement back and forth over the balls 65 8 to support the carriage now to be described.

Referring to Figures 2 and 3, there project upwardly from between the front ends of the tubes 9, 9, a pair of oppositely disposed legs 11, 11, of a guard 12. These legs 70 terminate at their lower ends in cupped ends 13, 13, which are brazed to the lower peripheries of the elongated tubes 9, 9. Behind the guard 12 there project between the elongated tubes 9, 9, two transverse carriage members 14, 14 having cupped ends 75 15, 15, similar to the cupped ends 13, 13 of the legs 11, 11 and likewise brazed to the lower peripheries of the elongated tubes 9, 9.

Below the transverse members 14, 14 is 80 a base plate 16 preferably constructed of one piece of metal having upturned sides in which are formed oppositely disposed notches 17, 17 to receive the ends of the transverse members 14, 14 by which the base 85 is moved back and forth for a purpose to be hereinafter described. The end sections of the notched sides of the base 16 are formed to provide outwardly projecting bearings 18, 18 at each end for a shaft 19 of a roller 90 20. (See Figures 1, 2, and 3). The bearings 18, 18 are reinforced by bronze pieces 21, 21 similar in shape to said bearings 18, 18 and riveted to the latter.

Around the rollers 20, 20 passes a wide 95 strip of canvas 22 or other flexible material whose free ends pass downwardly through a slot in the top 1, the forward free end being turned under said top and secured thereto by screws 23. The other free end of the 100 canvas 22 is sewed around a transverse rod 24 having vertically disposed flattened ends 25, 25. In each end 25 there is a threaded hole adapted to receive the threaded end of a bolt 26 loosely supported by two vertical 105 guides 27, 27 secured to the underside of the top 1. When this bolt is turned, it will draw its respective end of the rod 24 toward it to adjust the tautness of the canvas 22. (See Figures 1 and 4).

Nailed to the top 1 immediately in front of the slot that receives the free ends of

the canvas 22, is a strip of felt 28 the front end of which is sewed to the canvas at a point which will permit said felt to fully cover the opening 2 when the carriage is in its extreme forward position. Immediately behind the canvas 22 there is glued to the upper surface of the printing machine top 1, a board 29 of the same thickness and width as the felt 28, to present a level surface for the contact lid to roll upon. (See Figure 1).

In larger machines, for the purpose of increasing the pressure of contact, the following means are provided: Projecting up into recessed portions of the underside of the top 1, two on each side of the hole 2, are magnets 30. Each magnet 30 has a core 31 which projects upwardly through the top 1 to a point where the top of the core is flush with the upper surface of said top 1. The parts of the sides of the base 16 that were cut from the latter to form the notches 17, 17, are bent downwardly to a horizontal position as shown in Figure 6. To these horizontal sections designated by the numerals 31^a and 31^b there is riveted on each side of the machine, an elongated flat steel contact member 32. These members 32 when they come to a position over the magnet cores 31, will be drawn downwardly to them to increase the pressure of the felt 28 upon the picture that lies between it and the glass 3. This is due to the fact that when the members 32 are drawn downwardly, they will exert a downward pull upon the base 16 which presses against the felt 28.

For the purpose of resiliently exerting pressure upon the base 16 to cause the felt below it to press firmly upon the picture that lies between it and the glass, there is riveted to the undersurface of each transverse member 14 a leaf spring 33 whose free ends are curved upwardly to enable them to slide readily over the base 16 when the latter is raised during the printing of plates. (See Figures 2 and 5). The ends of the base 16 are also curved upwardly to enable it to slide over the felt 28 readily.

Secured to the top of the guard 12 is a handle 34 by means of which the entire carriage may be easily moved back and forth by the operator.

Before the operation of printing takes place, the carriage is moved back on the board 29 on the top 1, a sufficient distance to permit the felt 28 to clear the glass 3. Upon the latter the negatives and printing paper are then placed, after which the carriage is moved forward by the handle 34. During this forward movement of the carriage, the felt 28 is laid by the moving rollers 20 upon the negatives and printing paper as the self-laying track of a tractor is laid upon the ground. As soon as the felt 28 has covered the negatives and printing paper, contact is automatically effected by

the pressure of the springs 33 upon the base 16 above the felt. In larger machines, where the magnets 30 are used, this contact pressure will be increased by the attraction of the armature members 32 by the magnet 70 cores 31 when the printing lights are switched on.

It is thus seen that in my improved printing machine contact is automatically effected without the necessity of the operator pressing the printing lid against the glass or adjusting catches, which leaves both hands free during the entire exposure. The effort of moving the carriage back and forth is reduced to the minimum by the provision 80 of the ball bearings 8 over which the tubes 9, supporting the carriage, roll. Cleanliness is also secured by having the bearing parts enclosed in the tubes.

Having described my invention, I claim: 85

1. In a photographic printing machine, the combination with a top having a printing opening, of a transparent negative and paper-supporting medium in said opening, a carriage movable back and forth over said top, and a self-laying track whose free ends are secured to said top behind said printing opening therein adapted to be rolled by the carriage over the transparent medium to insure contact during the exposure of the 95 printing paper.

2. In a photographic printing machine, the combination with a top having a printing opening, of a glass for supporting negatives and paper over said opening, a carriage movable back and forth over said top, a pair of rollers pivotally secured within said carriage, and a strip of fabric whose free ends are secured to said top behind said opening, said fabric passing around said 105 rollers to be rolled thereby over said glass to insure contact during the exposure of the printing paper.

3. In a photographic printing machine, the combination with a top having a printing opening, of a transparent negative and paper-supporting medium in said opening, a carriage adapted to be moved over said medium, a member of magnetic material on said carriage and magnetic means in said 110 top adapted to attract the magnetic member of said carriage, to insure contact during the exposure of the printing paper.

4. In a photographic printing machine, the combination with a top having a printing opening, of a transparent negative and paper-supporting medium in said opening, a carriage adapted to be moved over said medium, a pair of magnets at each side of said opening, projecting into the said top, 125 a core in each magnet whose upper end is flush with the upper surface of said top, and armature members fixedly secured to said carriage, adapted to be attracted to said cores when the carriage is over said medium, 130

to insure contact during the exposure of the printing paper.

5. In a photographic printing machine, the combination with a top having a printing opening, of a glass for supporting negatives and paper over said opening, a pair of elongated tubes, transverse members secured between said tubes, a base anchored to said transverse members, a pair of bearings projecting from each end of said base, a roller pivotally secured in each pair of bearings, a strip of fabric whose free ends are secured to said top behind the opening, said fabric projecting beneath said base and over the rollers in a position to be rolled by them over said glass, and means secured to said top for supporting, with a minimum of friction, said tubes to permit to them a reciprocating movement, whereby said fabric may be rolled over and off the glass, for the purpose specified.

6. In a photographic printing machine, the combination with a top having a printing opening, of a glass for supporting negatives and paper over said opening, a pair of elongated tubes, transverse members secured between said tubes, a base, upturned sides on said base provided with notches to receive the transverse members, the front and rear sides of said base projecting forwardly and rearwardly respectively, a roller pivotally secured between the forwardly pro-

jecting side portions of the base, and a similar roller pivotally secured between the rearwardly projecting sides of said base, a strip 35 of fabric whose free ends are secured to said top behind the opening, said fabric projecting beneath said base and over the rollers in a position to be rolled by them over said glass, and means secured to said top for supporting, with a minimum of friction, the elongated tubes to permit to them a reciprocating movement, whereby said fabric may be rolled over and off the glass, for the purpose specified.

7. In a photographic printing machine, the combination with a top having a printing opening, of a glass for supporting negatives and paper over said opening, a pair of elongated tubes, a carriage adapted to be 50 moved by said tubes over and off said glass, brackets secured to said top, inward projections on said brackets, extending through longitudinal slots in said tubes, annular races on said projections within the tubes, 55 and balls in said races over which the inner peripheries of the tubes are adapted to move when the carriage is moved over or off said glass.

In testimony whereof I have hereunto set 60 my hand this 5th day of January, 1920.

JOHN J. ROTH.

Witness:

HOWARD S. SMITH.
